DEWAXING MINERAL OIL

Edwin C. Knowles, Beacon, N. Y., assignor to The Texas Company, New York, N. Y., a corporation of Delaware

Application September 20, 1935, Serial No. 41,393

5 Claims. (Cl. 196—18)

This invention relates to the separation of wax from oil.

The invention contemplates a process of dewaxing wax-bearing mineral oil containing either a naturally-occurring or an added wax crystal modifying substance, wherein the oil is mixed with a solvent liquid, the resulting mixture of oil and solvent heated to an elevated temperature, and the heated mixture thereafter chilled to precipitate the wax constituents which are subsequently removed.

The invention has particular reference to dewaxing relatively viscous oils having a Saybolt Universal viscosity above about 80 seconds at 210° F. as, for example, an oil of around 90 or 100 seconds at 210° F. and containing naturally-occurring asphaltic and resinous constituents which apparently modify the crystal form of the wax, as will be more fully explained below. The invention involves dewaxing oil of this character under conditions such that these naturally-occurring constituents apparently facilitate crystallization of the wax in a more readily separable and filterable form.

The invention is also applicable to dewaxing oils containing wax crystal modifying substances or materials which have been added thereto. I have found it advantageous to add wax crystal modifying material to relatively low viscosity oils which are deficient in the naturally-occurring modifying material above referred to, and then dewax them by the process of my invention.

The invention specifically contemplates heating the mixture of dewaxing solvent and wax-bearing oil containing such wax crystal modifying substance to a temperature of around 15° to 50° F. above the minimum temperature at which the oil and wax appears to be completely dissolved in the solvent, and thereafter chilling the heated mixture to a temperature of the order of 0° F. in order to precipitate the wax constituents in readily separable form.

I have discovered that when such wax-bearing oil and solvent mixture is subjected to heating at these elevated temperatures prior to chilling, there is a marked improvement in the character of the wax precipitated from the chilled mixture. The crystal structure of the wax is such that the wax is more readily separated from the mixture and can be more rapidly filtered therefrom. As a consequence, the filter rates can be increased ten or twelve times over the rate obtaining in the ordinary de-waxing procedure where the mixture of oil and solvent is not sub-

jected to the preliminary heating step of my invention.

The filter cake obtained by the practice of my invention is less voluminous, retains less oil, and comprises a higher content of paraffin wax. Furthermore, there is an increase in the yield of wax-free oil obtained as a result of following the procedure of my invention.

This improvement in filtration rate is apparently due to the beneficial change in the nature of the crystal formation of the wax precipitated from mixtures which have been subjected to the preliminary heating step, although the reason for this change in the crystal structure is not entirely understood.

It is my thought that, in the case of viscous oils, certain of the naturally-occurring asphaltic and resinous hydrocarbon constituents constitute wax crystal modifying substances. These constituents are believed to be less soluble than wax in the dewaxing solvent liquid, and at the minimum temperature at which the wax-bearing oil appears to be in complete solution, these constituents are not in true solution but rather are present as a colloidal solution.

In this form, these substances possibly form films on the small plate-type paraffin crystals formed during preliminary precipitation of the wax from the solution, and these films inhibit the normal transformation of the plate-type wax crystals into the more easily filterable type of crystals.

By heating to temperatures of 15° to 50° F. above this minimum temperature of apparent complete solution, these colloidal or low solubility substances are apparently completely dissolved in the solvent. It is believed that upon chilling the heated solution, they precipitate from the solution substantially co-extensively with the wax in the form of nuclear particles which actually facilitate crystallization of wax in a more readily separable and filterable form. It is thought that the optimum effect is realized when the modifying substance continues to precipitate from the solution over the entire range of wax crystallization.

I have found that the modifying action of added wax crystal modifiers may be greatly enhanced by the procedure of my invention, and particularly in the case of relatively less viscous oils as, for example, oils having a viscosity up to about 75 Saybolt Universal seconds at 210° F. Some improvement results, however, even in the case of the more viscous oils by adding some of this material thereto and proceeding by the method of this invention. Such added modifiers may

comprise small amounts of Montan wax, or synthetic modifying substances such as derived by condensation of chlorinated wax and naphthalene, and aluminum stearate, etc. The amount 5 of such modifying material added may be of the order of 0.20 to about 1% by weight of the wax-bearing oil.

It is thought that, as in the case of the naturally-occurring wax crystal modifying substances, 10 these added substances probably are precipitated from the previously heated solution in a form in which they act as nuclear particles serving to modify wax crystallization, with the result that the wax can be more readily filtered 15 from the chilled solution.

The minimum temperature at which the wax-bearing oil appears, on visual inspection, to be completely soluble in the dewaxing solvent, or in homogeneous admixture therewith, depends upon 20 the nature of the oil as well as upon the solvent. In the case of a selective dewaxing solvent of the character of a mixture of about 30% acetone and 70% benzol, for example, the minimum temperature of apparent complete solution of wax-bearing 25 oil in the solvent may range from around 90° to 125° F., the minimum temperature for relatively viscous oils being in the upper portion of 30 this temperature range.

My invention, therefore, comprises heating the 30 mixture of wax-bearing oil and selective solvent, such as a mixture of acetone and benzol, to temperatures in the range of about 125° to 175° F., and then chilling the heated mixture to temperatures of 0° F. and below in order to precipitate 35 the wax constituents. These wax constituents are then separated from the cold mixture, advantageously by filtration.

The invention is particularly advantageous as applied to the dewaxing of distillate and residual 40 wax-bearing oils which contain small amounts of asphaltic and resinous matter. For this reason, it is particularly adapted to dewax relatively viscous oils, including those which have been subjected to previous solvent refining action to remove 45 relatively low viscosity index constituents, and which are ordinarily rather difficult to dewax.

The improvement in filtration rate is indicated by reference to Figure 1 of the accompanying drawings. Curves A₁, A₂ and B in this figure 50 represent graphically the relationship between filtration rate and the temperature of heating prior to chilling in the case of dewaxing both a distillate and a residual type of stock, each of which had been previously subjected to solvent extraction for the removal of relatively low viscosity index constituents. Curves A₁ and A₂ relate to dewaxing the same distillate stock, while curve B relates to dewaxing the residual stock, 55 using methyl ethyl ketone and benzol as a dewaxing solvent. Laboratory inspection tests made on these two stocks gave the following 60 results:

65	Distillate stock	Residual stock
Gravity, °A. P. I.		
S. U. viscosity at 160° F.	26.9	28.4
S. U. viscosity at 210° F.	282	260
Percent carbon residue	112	107
Percent paraffin	.32	.29
Pour test °F.	11.5	10.9
	120	110-115

In both cases, the solvent comprised a mixture composed of 40% methyl ethyl ketone and 60% benzol, mixed with the oil in the proportion of 75

four parts of solvent mixture to one part of oil. After heating the mixture to the desired solution temperature, it was then introduced to a chilling vessel wherein it was chilled by indirect contact with cold brine to a temperature of -10° F. The 5 chilled mixtures were all filtered at this temperature to remove the wax and produce filtrates containing oil of about 0° F. pour. Filter rate calculations are all based on the passage of an equal volume of wax-free oil through the filter 10 surface, that is, 0.2 gallon of wax-free oil per square foot of filtering surface.

As shown by curve A₁ where the solvent and wax-bearing oil mixtures were heated to a temperature of only 120° F. prior to chilling, a filtration rate of about 1.7 gallons of wax-free oil per square foot of filtering surface per hour was realized. On the other hand, when the solution was heated to a temperature of 150° F. prior to chilling, the filter rate was increased to 24 gallons 20 of wax-free oil per square foot of filtering surface per hour.

It will be observed that heating the mixtures to temperatures in the range below 120° F. and also in the range above 160-170° F. does not appear to affect the filtration rate, but between these points the increase in filtration rate with increasing mixing temperatures is quite rapid.

In the experiments represented by curve A₁, the mixture of wax-bearing oil and solvent was 30 subjected during the chilling step to mild agitation by bubbling pre-cooled nitrogen gas through the mixture at the rate of about 4.8 cubic feet of gas per hour per square foot of horizontal cross-sectional area of the vertical chilling vessel. 35 The chilling vessel comprised a vertical cylindrical vessel, and the gas was introduced into the bottom thereof and caused to bubble upwardly through the mixture of oil and solvent contained therein.

Curve A₂ represents the filtering rates obtained with the same stock, using the same solvent but employing mechanical stirring instead of gaseous agitation. The mechanical stirring in this instance was effected by inserting a mechanical stirring arm into the same chilling vessel used in the preceding experiments. The stirring arm was rotated at a uniform rate of about five revolutions per minute.

Under these conditions, the optimum filtration 50 rate, when heating to temperatures of 150° F., is only about eight gallons of wax-free oil per square foot of filtering surface per hour. However, without such preliminary heating as, for example, when heating the oil and solvent to a 55 temperature of around 120° F., the filtration rate is only about one gallon per square foot of filtering surface per hour at the same rate of mechanical agitation.

It appears, therefore, that in order to realize 60 the optimum effect of preliminary heating, it is desirable to employ relatively mild agitation during the subsequent chilling step, and preferably the type of agitation such as is realized by bubbling a stream of gas at a relatively low rate 65 through the chilling mixture. Excessive mechanical agitation or violent agitation of any type tends to deform the wax crystals and render the wax much more difficult to filter.

Curve B represents the results obtained in the 70 case of a residual lubricating oil stock, and since mechanical agitation, rather than gaseous agitation, was employed in chilling the solutions of residual oil and solvent, the curve is very similar to curve A₂ for the distillate oil dewaxed under 75

the same conditions. In any case, as shown by curve B, heating the mixture of residual stock and solvent to a temperature of about 160° F. results in a very great increase in the rate of filtration. The general characteristic of curve B is similar to that of curve A₁, indicating that the application of the process of this invention to residual stocks produces the same improved results as in the case of viscous distillate lubricating oil stocks, providing that the mixture, during the chilling step, is subjected to relatively mild agitation.

The following tabulation affords a comparison of the effect upon filter rates by varying the degree and type of agitation employed during the chilling step in dewaxing a distillate stock, such as that described above, with the same proportion of solvent mixture of the same solvent composition:

20

Mechanical agitation

25

Temperature of solution prior to chilling	Revolutions per minute	Filter rate—gallons of wax-free oil per square foot per hour
°F.		
165	140	1.3
165	140	1.2
165	100	1.4
165	55	2.3
165	5	11.4

Gaseous agitation

35

Temperature of solution prior to chilling	Cubic feet of gas per square foot per hour	Filter rate—gallons of wax-free oil per square foot per hour
°F.		
170	15.1	16.8
170	4.8	16.8
170	1.6	12.0
150	22.0	12.5
150	18.0	15.3
150	15.1	17.7

In making these comparisons, the mixture of wax-bearing oil and solvent was subjected to chilling in the same chilling vessel, regardless of the type of agitation employed. Mechanical agitation comprised the insertion of a rotating stirrer in the chilling vessel which was caused to revolve at rates varying from 5 to 140 revolutions per minute.

55 The gaseous agitation was effected by bubbling nitrogen gas through the mixture in the chilling vessel, with the stirrer removed, at rates of from 1.6 to 22 cubic feet of gas per hour per square foot of horizontal cross-sectional area of the vertical chilling vessel.

In the runs in which the mechanical stirrer was employed, the mixture of wax-bearing oil and solvent was heated to the same solution temperature of 165° F. prior to chilling. The results obtained indicated that where rapid mechanical agitation is employed as, for example, at rates of around 50 to 140 revolutions per minute of the stirrer, the filtration rate is relatively low, in the neighborhood of one or two gallons per square foot of filtering surface per hour. However, by reducing the stirring rate to around five revolutions per minute, there is a very marked increase in the filtration rate; that is, with this low rate of stirring, a filter rate of 11.4 gallons

per square foot of filter surface area per hour was realized.

It will be observed, however, that in general much higher rates of filtration were realized where gaseous agitation was employed. There was less variation in the filter rate over the range investigated, and the results indicated that when the mixture undergoing chilling is agitated, by bubbling gas through it at the rate of about 4.8 cubic feet of gas per hour per square foot of 10 cross-sectional area, a high filter rate is obtained.

It appears, therefore, that when the mixture is agitated by bubbling gas therethrough at a relatively low rate, the wax crystals are subjected to less deformation than when subjected to 15 mechanical stirring. Mild agitation, of course, is necessary in order to realize uniform chilling of the mixture.

I have also found that the obtaining of the maximum degree of benefit by preliminary heating of the wax-bearing oil and solvent is dependent upon employing the proper ratio of solvent mixture to oil. In the case of oils up to about 75 seconds viscosity at 210° F., a suitable mixture comprises one part of oil to one part of solvent. For more viscous oils, the mixture may comprise two parts of solvent to one part of oil. Larger proportions of solvent may be used if desired as, for example, as high as four or six parts of solvent to one part of oil.

30 In order to more fully describe the operation of my invention, reference will now be made to Figure 2 of the drawings, illustrating a method of flow adapted to the practice of my invention.

Wax-bearing oil from a source not shown is 35 delivered by a pump 1 to a mixer and heater 2. The dewaxing solvent, from a source not shown, is delivered by a pump 3 to the mixer and heater 2 wherein it undergoes mixing with the wax-bearing oil, and the resulting mixture is heated 40 to a super-solution temperature, for example, in the range of about 130° to 170° F.

From this mixer, the heated mixture is then conducted through a pre-cooler 5 wherein it is cooled by indirect heat exchange with a cooling 45 medium which may comprise water.

The cooled mixture is thereafter conducted through heat exchanger 6 wherein it is further cooled as, for example, by indirect heat exchange with a flowing stream of dewaxed oil, leaving the 50 filter referred to later.

The resulting cooled mixture is then introduced to the top of a vertical pipe chiller or series of such vertical pipe chillers 7. The chiller 7 advantageously comprises a vertical vessel provided with an annular jacket through which cold brine is circulated.

This chiller 7 is provided with an internal scroll type of scraper 8 adapted to scrape adhering wax from the interior surfaces of the chiller. A distributor 9 is positioned in the bottom of the chiller for introducing gas to the lower portion thereof.

The mixture of wax-bearing oil and solvent introduced to the upper portion of the chiller 7 moves downwardly therethrough countercurrently to the rising gas, which latter is introduced at a rate sufficient to effect relatively mild agitation of the body of liquid within the chiller 7.

From the bottom of the chiller 7, the chilled 70 mixture, at a temperature of the order of 0° F. and below, and containing precipitated wax, is removed, either directly to a filter 10, or to a surge tank 11.

The surge tank 11 also advantageously com-

75

prises a vertical vessel provided with means for introducing gas through a distributor 12 for the purpose of maintaining the contents in a gently agitated condition.

5 The filter 10 advantageously comprises a continuous type of vacuum filter by means of which the precipitated wax is removed from the cold solution as a filter cake.

10 The resulting filtrate, which is still at a low temperature, may be passed, all or in part, in heat exchange relationship with the fresh charge flowing through the heat exchanger 6.

15 Thereafter, the warm dewaxed solution is conducted to a solvent recovery system not shown, wherein the solvent is stripped from the dewaxed oil and returned for further use.

20 The gas used for agitation purposes in the chiller 7 and the surge tank 11 may comprise any suitable inert gas, such as carbon dioxide, nitrogen, flue gas, or a volatile petroleum hydrocarbon.

The make-up gas is taken from a gasometer 13 by means of a pump or compressor 14 and delivered along with the recycling gas to the lower portion of a gas chiller 15 wherein it is chilled 25 to the appropriate temperature, preferably around 0° F. and below.

In the gas chiller 15, the circulating gas is brought into indirect heat exchange relationship with a refrigerant, such as vaporizing ammonia.

30 If desired, the circulating gas may be caused to bubble through a body of liquid, such as a portion of the dewaxing solvent, which is maintained in indirect contact with a refrigerant fluid.

35 It may be of advantage to employ the latter means of cooling the circulating gas so that the latter will always be saturated with dewaxing solvent vapor, and thus not disturb the ratio of solvent to oil being maintained within the chiller 7.

40 The chilled circulating gas is conducted from the upper portion of the gas chiller 15 to the distributor 9 in the bottom of the chiller 7.

45 In a similar manner, a portion of the chilled gas is circulated through the contents of the surge tank 11, and from there returned to the gas chiller 15.

50 As a specific example in the carrying out of the process of my invention, a sample of wax distillate was first extracted with furfural to remove the relatively low viscosity index constituents, then dewaxed according to the following procedure.

55 This wax distillate was derived from Mid-Continent crude, and after solvent extraction with furfural had tests similar to those of the distillate stock already referred to in connection with the discussion of Figure 1.

60 This furfural-refined-wax distillate was mixed with a mixture consisting of 40% methyl ethyl ketone and 60% benzol in the proportion of four parts of solvent mixture to one part of distillate. This mixture of oil and solvent was then heated to a temperature of 140° F.

65 Following this, the hot mixture was cooled to a temperature of -10° F. during which cooling it was subjected to mild agitation by bubbling nitrogen gas therethrough. The cooling was effected in a vertical cylindrical vessel provided with means for introducing gas to the lower portion thereof. The gas was thus introduced to the chilling vessel at the rate of about five cubic feet per hour per square foot of horizontal cross-sectional area of the chiller.

70 The cold mixture was then filtered in a vacuum filter to remove the solidified wax as a filter

cake. The filter cake was removed without washing with a solvent. This cake, after removal of the solvent, comprised slack wax containing around 44% to 46% of paraffin wax of 146° to 148° F. melting point.

75 The filtrate, after removal of the solvent, had a pour test of around 0° F. and comprised 71% of the undewaxed distillate. This filtrate was produced at the rate of 22 to 25 gallons per hour per square foot of filtering surface, when calculated on the basis previously given.

The results thus obtained indicated that the filter rate was increased approximately twelve times over that obtained when the mixture of wax-bearing oil and solvent was not subjected to heating above 115° or 120° F. prior to chilling. The yield of wax-free oil, without subjecting the filter cake to a solvent wash, was increased around 10%. At the same time, the volume of the wax cake was about 35% less, while the paraffin wax content of this wax cake was increased by about 7% or 8%.

20 The filter cake comprised crystalline wax which was compact and relatively free from oil, characterized by the fact that it filtered or drained quite easily as contrasted with the mushy, bulky and slow-filtering filter cakes obtained in prior methods of dewaxing.

25 While a specific example using a solvent mixture composed of methyl ethyl ketone and benzol has been referred to, nevertheless the method of this invention is also applicable to dewaxing with other solvents or solvent mixtures. I have found that substantially the same results are obtained when employing a solvent mixture 30 consisting of 30% acetone and 70% benzol with the same wax-bearing stock.

35 As examples of other solvents which may be used in connection with this invention, methyl isobutyl ketone may be mentioned, and mixtures of methyl ethyl ketone and aliphatic ethers, such as isopropyl ether and dibutyl ether. I have found that the method of this invention is particularly advantageous in the case of mixtures consisting of about equal parts of methyl ethyl 40 ketone and isopropyl ether, for example.

45 Solvent mixtures composed of mixed aliphatic ketones, such as a mixture of dipropyl ketone with methyl ethyl ketone or with methyl isobutyl ketone, may also be advantageously employed in 50 the practice of my invention.

55 I have found that the application of the step of heating the wax-bearing oil and solvent mixture prior to chilling produces improved results in the case of dewaxing with the foregoing 55 solvents or solvent mixtures.

60 Thus, for example, when dewaxing the above lubricating oil distillate stock and methyl isobutyl ketone, I have found that a filtering rate as high as 63 gallons per square foot of filtering surface 60 per hour may be obtained by first heating the mixture of oil and solvent to a temperature of 175° F. prior to chilling. This is to be compared with a filtering rate of only about one gallon per square foot of filtering surface per hour where 65 the mixture is not heated to temperatures above 130° F. prior to chilling. This comparison was made using four parts of solvent to one part of oil and dewaxing at 0° F. to produce an oil of around zero pour test.

70 The examples referred to above specifically describe dewaxing relatively viscous oils. It is contemplated, however, that the invention is applicable to the treatment of relatively less viscous oils containing wax crystal modifying substances. 75

Obviously, many modifications and variations of the invention, as hereinbefore set forth, may be made without departing from the spirit and scope thereof, and therefore only such limitations should be imposed as are indicated in the appended claims.

I claim:

1. The method of separating wax from mineral oil which comprises mixing the oil and wax containing wax crystal modifying material with a selective solvent such that the wax and oil appear to be completely dissolved therein at a temperature not in excess of about 125° F., and such that upon chilling a mixture of the oil and solvent to precipitate wax, and removing the wax so precipitated, the resulting dewaxed oil, after removal of the solvent, will have a pour test corresponding substantially to the temperature at which the wax was removed, heating the solution to a temperature above 150° F. such that upon chilling to about 0° F. and filtering, the rate of filtration is substantially greater than that obtained, and a wax cake is secured having a bulk not more than two-thirds the bulk secured, by heating only to about 125° F., chilling the heated mixture to precipitate wax and removing the wax thus precipitated.
2. The method, according to claim 1, in which the selective solvent comprises a mixture consisting of a low molecular weight aliphatic ketone and an aromatic hydrocarbon.
3. The method, according to claim 1, in which the selective solvent comprises an aliphatic ketone containing up to seven carbon atoms.
4. The method of separating wax from mineral oil which comprises mixing the oil and wax containing wax crystal modifying material with a selective solvent such that the wax and oil appear to be completely dissolved therein at a temperature

not in excess of about 125° F., and such that upon chilling a mixture of the oil and solvent to precipitate wax, and removing the wax so precipitated, the resulting dewaxed oil, after removal of the solvent, will have a pour test corresponding substantially to the temperature at which the wax was removed, heating the solution to a temperature around 160 to 170° F. such that upon chilling to about 0° F. and filtering, the rate of filtration is substantially greater than that obtained, and a wax cake is secured having a bulk not more than two-thirds the bulk secured, by heating only to about 125° F., chilling the heated mixture to precipitate wax and removing the wax thus precipitated.

5. The method of separating wax from mineral oil which comprises mixing the oil and wax containing wax crystal modifying material with a selective solvent comprising a mixture of a low molecular weight aliphatic ketone and an aromatic hydrocarbon such that the wax and oil appear to be completely dissolved therein at a temperature not in excess of about 125° F., and such that upon chilling a mixture of the oil and solvent to precipitate wax, and removing the wax so precipitated, the resulting dewaxed oil, after removal of the solvent, will have a pour test corresponding substantially to the temperature at which the wax was removed, heating the solution to a temperature around 160 to 170° F. such that upon chilling to about 0° F. and filtering, the rate of filtration is substantially greater than that obtained, and a wax cake is secured having a bulk not more than two-thirds the bulk secured, by heating only to about 125° F., chilling the heated mixture to precipitate wax and removing the wax thus precipitated.

EDWIN C. KNOWLES.
